CLAIM

We claim the ornamental design for a portable computer, as shown and described.

DESCRIPTION

FIG. 1 is a front perspective view of a first embodiment of a portable computer of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is an end view taken along the line 8-8 of FIG. 4 with the internal parts being omitted thereof; and,

FIG. 9 is an end view taken along the line 9-9 of FIG. 4 with the internal parts being omitted thereof.

FIG. 10 is a front perspective view of a second embodiment of a portable computer of the present invention;

FIG. 11 is a front view thereof;

FIG. 12 is a rear view thereof;

FIG. 13 is a first side view thereof;

FIG. 14 is a second side view thereof;

FIG. 15 is a top view thereof;

FIG. 16 is a bottom view thereof.

FIG. 17 is an end view taken along the line 17-17 of FIG. 13 with the internal parts being omitted thereof; and,

(Continued)

FIG. 18 is an end view taken along the line 18-18 of FIG. 13 with the internal parts being omitted thereof. The broken lines shown in the drawings represent portions of the portable computer that form no part of the claimed design. The dash-dot-dot lines indicate the areas of the section views and form no part thereof.
